UNITED STATES PATENT OFFICE

2,021,368

BEVERAGE DELIVERING APPARATUS

Martin Louis, Essen, Germany, assignor to Fried.
Krupp Aktiengesellschaft, Essen-on-the-Ruhr,
Germany

Application September 6, 1933, Serial No. 688,400
In Germany July 13, 1933

10 Claims. (Cl. 225—18)

My invention relates to beverage delivering apparatus, such as siphons for beer and other beverages, beverage vending apparatus of the penny-in-the-slot system as used in automatic restaurants, and like apparatus.

One of the requirements to be met by apparatus of this class is the possibility of cooling the beverage and of maintaining it in cooled condition. My invention therefore has for its object 10 to provide very simple and efficacious means for cooling and keeping cold the beverage to be delivered by the apparatus.

In order that my invention may be clearly understood and readily carried into effect, a preferred embodiment of the same is illustrated by way of example in the drawings which accompany and form part of this specification. In these drawings

Figure 1 is a vertical section of a portable siphon 20 constructed in accordance with my invention, and

Figure 2 is a similar section showing a modified use of the cooling device of the siphon.

Referring to these drawings, 1 denotes a jacket which forms the outer shell of the siphon and 3 is the shell of the liquid container 4, the space 2 formed between the jacket 1 and the liquid container 4 constituting the container for the pressure medium, such as carbon dioxide. The liquid container 4 is closed at top by a cover 5 in the center of which is mounted the tap valve with spout and the ascension pipe 6. Between the pressure medium container 2 and the liquid container 4 is arranged in known manner a valve 7 adapted to manually regulate from outside the supply of the carbon dioxide to the liquid container. The cover 5 has an aperture 8 surrounded by an outer flange 9 externally fitted with a reinforcing ring 10. The aperture 8 serves to introduce into the liquid container 4 a cooling body 11 which preferably has the shape of a tube closed at bottom and open at top and which for use can be filled with ice. On its open top end the tube 11 is provided with an external offset ring 12 which on its lower portion of larger diameter carries female threads, so that it can be screwed thereby onto the reinforcing ring 10 of the cover flange 9, while its upper portion of smaller diameter carries male threads onto which a cap nut or cover 13 can be screwed, which thus closes the open end of the cooling tube 11. The size and pitch of these threads are such that the cover 13 can be screwed also onto the reinforcing ring 10. The cover 5 of the liquid container 4 is of such a convex shape and the aperture 8 with its flange 9 is disposed in such a manner that the cooling

tube when inserted is normal to the respective curvature of the cover 5. The lower end of the cooling tube 11 thus is in the close vicinity of the lower end of the ascension pipe 6.

As the cooling tube 11 thus is introduced into the liquid container 4 from above, this introduction can be effected even after the liquid container has been filled with the beverage. Furthermore, since the aperture 8 can be closed airtight by the cover 13, it is possible to use the siphon also without the cooling tube 11. The arrangement of the regulating valve 7 affords the advantage of the siphon, after the liquid container 4 has been opened in order to apply or remove the cooling tube, not needing to be recharged with carbonic acid, provided the container 2 from the first has amply been filled with carbon dioxide. Alternatively the outer wall 1 may be provided with a nipple device 26 for charging the space 2 with carbon dioxide, as shown in Fig. 2.

Generally the cooling tube will be filled with ordinary ice or with dry ice. If these two cooling means are not at disposal, but a domestic refrigerating machine is present which has but a comparatively small freezing chamber, the device hereinafter described is made use of with advantage.

As indicated in Figure 1 the cooling means proper is subdivided into a plurality of individual interconnected cooling bodies 14 which are of such a size that a sufficient number thereof can be placed in the freezing chamber of the refrigerating machine. The individual bodies are preferably formed by hollow metallic balls and are filled up to about half their volume with water which then freezes in the freezing chamber. They are interconnected by short chains 16 whilst one of the end bodies 14 carries a longer chain 17 by means of which the entire string of cooling balls 14 can be fixed to a suitable hook 18 provided on the inner side of the cover 13.

The described subdivided cooling means afford two possibilities of use. If a quick cooling action is desired and an opening of the liquid container does not harm the quality of the beverage the individual cooling bodies 14 can be hung directly into the liquid container, as illustrated in Figure 2. Preferably the length of chain 17 is such that the greater part of the cooling balls 14 then rests on the bottom of the liquid container. Otherwise the string of cooling balls 14 can be introduced in the cooling tube 11 which then forms a space for the reception of the cooling balls which is closed from the liquid container 55

4. In this case it will be of advantage to fill the tube 11 with water in order to obtain a good transfer of the coldness from the cooling balls through the wall of tube 11 to the beverage in the container 4.

5. What I claim and desire to secure by Letters Patent is:—

1. In a beverage delivering apparatus of the class described a liquid container and a pressure medium container forming a jacket for the former, liquid delivery means on the top of said liquid container, an aperture on the top of said liquid container, a cooling member adapted to be introduced into the latter through said aperture, and means for air-tightly closing said aperture both after introduction and withdrawal of said cooling member.

2. In a beverage delivering apparatus of the class described a liquid container and a pressure medium container forming a jacket for the former, a pressure-regulating valve manipulatable from outside inserted between said two containers, liquid delivery means on the top of said liquid container, an aperture on the top of said liquid container, a cooling member adapted to be introduced into the latter through said aperture, and means for air-tightly closing said aperture both after introduction and withdrawal of said cooling member.

3. In a beverage delivering apparatus of the class described a liquid container and a pressure medium container forming a jacket for the former, liquid delivery means on the top of said liquid container, an outwardly flanged aperture on the top of said liquid container and external threads on said flange, a cooling member adapted to be introduced into said liquid container through said aperture and fitted on top with female threads fitting in the threads of said flange and with external threads, and a cap nut fitting both in the external threads of said cooling member and in those of said flange.

4. In a beverage delivering apparatus of the class described a liquid container and a pressure medium container forming a jacket for the former, liquid delivery means on the top of said liquid container, an aperture on the top of said liquid container, a cooling member formed by a string of individual cooling bodies adapted to be introduced into said liquid container through said aperture, and means for air-tightly closing said aperture both after introduction and withdrawal of said string of cooling bodies.

5. In a beverage delivering apparatus of the class described a liquid container and a pressure medium container forming a jacket for the former, liquid delivery means on the top of said liquid container, an outwardly flanged aperture on the top of said liquid container and external threads on said flange, a hollow body closed at the bottom and adapted to receive a cooling means and to be introduced into said liquid

container through said aperture and fitted on top with female threads fitting in the threads of said flange and with external threads, and a cap nut fitting both in the external threads of said hollow body and in those of said flange. 5

6. In a beverage delivering apparatus of the class described a liquid container and a pressure medium container forming a jacket for the former, liquid delivery means on the top of said liquid container, an outwardly flanged aperture 10 on the top of said liquid container and external threads on said flange, a hollow body closed at the bottom and adapted to receive a cooling means and to be introduced into said liquid container through said aperture and fitted on top 15 with female threads fitting in the threads of said flange and with external threads, and a cap nut fitting both in the external threads of said hollow body and in those of said flange, said cooling means consisting of a string of individual 20 cooling members, and means for fixing said string of cooling members to said cap nut.

7. An apparatus as specified in claim 6, in which said individual cooling members are formed by hollow balls adapted to receive a cool- 25 ing means.

8. An apparatus as specified in claim 6 in which said individual cooling members are formed by hollow balls interconnected by flexible metallic traction members and adapted to receive a cooling means.

9. In a beverage delivering apparatus of the class described a liquid container and a pressure medium container forming a jacket for the former, liquid delivery means on the top of said liquid container, an aperture on the top of said liquid container, a cooling member formed by a string of individual cooling bodies adapted to be introduced into said liquid container through said aperture, and means for air-tight- 40 ly closing said aperture both after introduction and withdrawal of said string of cooling bodies, said string being dimensioned in such a manner that the greater part of said individual cooling bodies when applied comes to lie on the bottom 45 of said liquid container.

10. In a beverage delivering apparatus of the class described a liquid container and a pressure medium container forming a jacket for the former, said liquid container having a convex 50 cover, liquid delivery manipulative means disposed centrally on said cover and including an ascension pipe extending down to the bottom of said liquid container, an aperture eccentrically situated in said cover, a cooling member adapt- 55 ed to be introduced into said liquid container through said aperture in such a direction that its lower end is in the vicinity of the lower end of said ascension pipe, and means for air-tight- 60 ly closing said aperture both after introduction and withdrawal of said cooling member.

MARTIN LOUIS.
